United States Patent Office.

JAMES W. EVANS, OF NEW YORK, N. Y.

Letters Patent No. 69,421, dated October 1, 1867.

IMPROVED MACHINE FOR COILING SPRINGS.

The Schedule referred to in these Letters Patent and making part of the same.

TO ALL WHOM IT MAY CONCERN:

Be it known that I, JAMES W. EVANS, of the city, county, and State of New York, have invented a certain new and useful improvement on Machines for Manufacturing Spiral Springs, of which the following is a full, clear, and exact description, reference being had to the accompanying drawing, forming part of this specification, and in which—

Figure 1 represents a side elevation of a machine for making spiral springs, constructed according to my improvement.

Figure 2 a plan of the same, and

Figure 3 a transverse section through the line X X in figs. 1 and 2.

Like letters indicate like parts throughout the several figures.

The nature of my invention, which relates to the manufacture of railroad-car and other spiral springs from rod or wire, consists in a novel combination of a revolving mandrel, on which the wire is wound, with a rotating spirally-grooved cylinder or roll for directing the wire in a uniform manner to its wrap on the mandrel, and securing to it a close hug on the latter at any desired pitch; also, said invention farther consists in a novel combination of sliding mandrel and locking attachment for holding the wire in producing the wrap, and for detaching the coiled spring when formed.

Referring to the accompanying drawing, A represents the bed of the machine, and B B standards for supporting a rotating mandrel-shaft, C, which carries fast and loose pulleys D E, and is made capable of sliding longitudinally by, it may be, means of a lever, F, locking, when said shaft is moved to its extreme forward position, in a spring-catch, G. The shaft C also is or may be provided with a hand-turning wheel, H, for adjusting it circumferentially to establish the lock of the wire on the mandrel, as hereinafter described. Fitted to the inner end of the shaft C, so as to rotate with it, and form, as it were, an extension of it, is a mandrel or mandrel-rod, I, preferably made detachable, for the substitution, when required, of a mandrel of different diameter or length, or both, according to the sized core and length of the spring to be made. The connection of the mandrel I with the shaft C may be through a box or swell, a, fitted with a rocking-dog or lever, b, operated by a screw, c, and projecting through the inner end or face of said box, to establish a locking grip or hold on the wire to the mandrel at its one end, where is arranged a spiral collar, d, to guide the wire to the dog. J J' are standards arranged at any suitable distance apart, and the outer one, J, of which, is preferably made adjustable on the bed in which it rests, to vary the distance apart of said standards to adapt the machine to the production of different lengths of springs. This outer standard J forms bearings to pinions e e, having socket or clutch-box constructed shafts f f, into one of which the outer end of the mandrel I fits, and with which it gears so as to rotate the one pinion that in its turn gives motion to the other pinion, the socket of which has gearing with it a spirally-grooved cylinder or roll, K, arranged parallel to the mandrel, and rotating in close relationship thereto by its support in the socket of the pinion with which it gears, and in a bearing in the standard J', through which the mandrel-connecting box a also fits. This spirally-grooved cylinder or roll K guides the wire to its proper wrap on the mandrel, and should be made detachable, so as to substitute others of different diameter, pitch, or length, according to the size or pitch of the spring required to be made. Where the coiled spring to be produced is of a tapering or conical form, instead of straight, then the mandrel and spirally-grooved guiding-roll should be shaped accordingly.

To manufacture a spring by this, my improvement, supposing the mandrel I to be slid forward to the position represented for it in fig. 1, and its shaft C turned by the hand-wheel H, so as to bring the dog b in line with or under a notch, s, in the roll K, so that said dog may be opened by the screw c to receive in grip the end of the wire guided to it over a rest or bar, m, and by the spiral collar d; then, on giving motion to the mandrel-shaft, and through gear described, to the spirally-grooved roll, the wire, heated, it may be, to any required degree, is wrapped on the mandrel, its twist and close hug of the same being regulated by the spirally-grooved guiding-roll K, which gives to the spring so formed a uniform spiral construction of a compact and firm character. When the wire has been wound on the mandrel the required length, which may be the length of the mandrel or less, the dog b is released by suitably turning the screw c from its grip on the end of the wire, when, by drawing the mandrel back, as represented in fig. 2, the spring is shoved or drops off the mandrel, and the

machine, on adjusting the mandrel and its locking-dog, as hereinbefore described, is ready for the manufacture of a fresh spring.

What I claim as my invention, and desire to secure by Letters Patent, is—

1. The revolving mandrel I, made capable of a sliding motion in direction of its length, in combination with the spirally-grooved roll K, and serving to detach the spring when formed, essentially as herein set forth.

2. In combination with the sliding and revolving mandrel I, the gripping-dog b, and spiral guiding-collar d, for operation on the wire of which the spring is formed, substantially as specified.

3. The sliding and revolving mandrel I, with its locking-dog b and band-wheel, or its equivalent, II, in combination with the spirally-grooved rotating roll K, having formed in it a recess or notch, s, essentially as herein set forth.
